ELECTRICAL CONNECTION MEANS

Harry A. Douglas, Bronson, Mich., assignor to
Kingston Products Corporation, a corporation
of Indiana

Application May 31, 1935, Serial No. 24,253

7 Claims. (Cl. 173—328)

My invention relates to electrical connection means, and more particularly to connection means mountable on a base, or on the casing of an electrical device, and the principal object of my invention is to provide a new and improved electrical connection means. In the drawing accompanying this specification and forming a part of this application, I have shown, for purposes of illustration, one form which my invention may assume. In this drawing:

Figure 1 is an elevational view, partly in vertical longitudinal section, of a connection means embodying my invention, comprising a plurality of terminal connectors mounted on a fragmentarily shown casing,

Figure 2 is a vertical sectional view along the line 2—2 of Figure 1, looking in the direction of the arrows,

Figure 3 is a horizontal sectional view along the line 3—3 of Figure 1, looking in the direction of the arrows, showing the base fragmentarily and only one of the terminal connectors, and

Figure 4 is a perspective view of a detail. Referring to Figure 1 of the drawing, the connection means is here shown as associated with a casing 10, which may be a casing of any desired electrical device, the casing 10 carrying an insulating base 11 in turn carrying terminals 12, 13, and 14. While three terminals have been illustrated, it will be understood that any number of terminals, one or more, may be utilized, depending upon the connections desired to be made. The insulating base 11 is in this instance larger than an aperture 15 in the casing 10 and may be held to the casing by tongues 16, 17, which may be struck up from the casing and clinched over the insulating base.

In the illustrated embodiment of my invention all of the terminals 12, 13, 14 are alike and therefore a detailed description of one of them applies to all of them, so that it will be understood that the terminals 12, 13 show in elevation the same form of terminal as the terminal 14, the latter being shown in vertical longitudinal section in Figure 1. The terminal 14 comprises a tubular body portion 18, which is of oblong rectangular cross-section, as shown in the horizontal section of Figure 3, having opposite walls 19, 20, in this instance shorter than opposite walls 21, 22 at right angles to the walls 19, 20. The longer wall 21 is, in this instance, formed in halves, one half 23 being integral with the wall 19 and the other half 24 integral with the wall 20. In like manner the longer wall 22 is formed in halves,

one half 25 being integral with the wall 19 and the other half 26 integral with the wall 20. The shorter walls 19, 20 are integrally joined by a U-shaped loop portion 27, forming an aperture 60, whose axis is at right angles to the axis of 5 the tubular body portion 18. The edges of the loop 27 may be tapered from the bight of the loop to the junction between the legs of the loop and the walls 19, 20, as indicated at 28, 29 (Figure 2). The upper ends of the walls 21, 22 may 10 be trimmed so as to form an arcuate edge 59 concentric with the aperture 60, if desired.

The walls 19, 20 have their lower ends 30, 31, as viewed in Figure 1, in abutment with the upper surface of the insulating base 11. The 15 lower ends of the walls 19, 20 may be bent outwardly slightly, if desired, so that the places of abutment between the lower ends 30, 31 of the walls 19, 20 and the upper surface of the insulating base 11 will be further apart.

The walls 21 and 22 are provided with extensions 32, 33 and 34, 35 respectively, adapted to be received in a square aperture 36 in the base 11, and in this instance these extensions are made long enough to extend beyond a plate 37 20 shown abutting the lower surface of the base 11. The wall extensions 32, 33 desirably have a combined width less than the wall 21 and of a combined width to snugly fit the width of a margin of the aperture 36. The wall extensions 34, 35 25 30 are formed of a combined width similar to that of the wall extensions 32, 33. These wall extensions have ends 38, 39 and 40, 41 respectively extending through slots 42, 43 in the plate 37 and clinched over the plate 37, to firmly hold the 35 40 45 abutting ends 30, 31 of the walls 19, 20 against the upper face of the insulating base and to firmly hold the plate 37 against the lower face of the insulating base.

The plate 37 is provided with an ear 44 extending at right angles from the plate, to serve as a convenient terminal for the connection of an electrical conductor. For this purpose the ear 44 may also be provided with a hole 45 through which a conductor 46 may be inserted, the conductor being then soldered to the ear 44.

Within the tubular body 18 of the terminal 14 is disposed a detent means 47, which is here shown as U-shaped, the bight 48 of the U being generally flat but provided with an approximately semi-cylindrical protuberance 51 whose axis is at right angles to the axis of the aperture 60. The protuberance 51 may be formed by striking out the metal of the bight 48, the detent means 47 being desirably formed of sheet metal. 55

The legs 49, 50 of the U-shaped detent means are adapted to slide along the inside surfaces of the walls 19, 20 and are also guided by the inside surfaces of the walls 21, 22. Upward motion 5 of the detent means 47, as viewed in Figure 1, is limited by shoulders 52, 53 extending inwardly toward each other from the upper ends of the walls 19, 20 at substantially the junction of these walls and the loop 27. The detent means 47 is 10 biased upwardly by means of a spring 54, one end of which bears against the underside of the bight 48 of the U-shaped detent means and the other end of which bears against the plate 37.

The spring 54 biases the detent means toward 15 the axis of the aperture 60 and therefore against an electrical conductor terminal 56 adapted to be inserted in the aperture 60. The conductor terminal 56 includes a cylindrical portion having an annular furrow 55, in which the protuberance 51 20 of the detent means is adapted to be seated when the terminal 56 snaps into the position shown in Figures 1 and 2. The terminal 56 is provided with a frustro-conical end 57 which serves to cam the detent means 47 downwardly against the bias 25 of the spring 54 as the terminal 56 is inserted into the aperture 60. The terminal 56 may be fastened to a conductor disposed therein by swedging, as indicated by the swedge indentations 58.

It will be evident from the foregoing description 30 of the illustrated embodiment that the terminal 14 is desirably made of sheet metal, the walls 19, 20, 21, 22 being formed to the desired shape and the channel shaped halves of the body 18 being then bent toward each other until the 35 longitudinal opposed edges of the halves 23, 24 and 25, 26 meet in lines of registry 61, 62, to form the tubular body 18. By so bending the halves of the body 18 toward each other, the loop 27 is formed. The terminal 14 may be assembled with 40 the base by inserting the wall extensions 32, 33 and 34, 35 through the aperture 36, the detent means 47 and the spring 54 being either then inserted into the tubular body 18 of the terminal or before the body of the terminal is thus assembled 45 with the base. The plate 37 is then brought against the spring 54 and against the insulating base 11, with the slots 42, 43 in the plate in registry with the wall extensions 32, 33 and 34, 35 and the wall ends 38, 39, 40, 41 are then 50 clinched over the plate 37.

From the foregoing it will be apparent to those skilled in the art that the illustrated embodiment of my invention provides a new and improved electrical connection means, readily and conveniently constructed and assembled, and accordingly, accomplishes at least the principal object of my invention. On the other hand, it also will be obvious to those skilled in the art that the illustrated embodiment of my invention may 55 be variously changed and modified, or features thereof, singly or collectively, embodied in other combinations than those illustrated, without departing from the spirit of my invention, or sacrificing all of the advantages thereof, and that 60 accordingly, the disclosure herein is illustrative only, and my invention is not limited thereto.

I claim:

1. A conductor terminal receiving means, 70 adapted to be assembled with a base having an aperture, comprising: a tubular body portion of generally rectangular cross-section, said body portion having opposed walls provided with a bent-out part adapted to abut a surface of said base, and having other opposed walls provided 75 with integral extensions adapted to pass through

said aperture and be clinched against the other surface of said base.

2. In combination: an insulating base having an aperture; a plate having apertures, disposed on one side of said base, providing means for electrical connection; and a sheet metal tubular electrical conductor receiving means, of polygonal cross-section, certain of the walls thereof being formed to abut the opposite surface of said base, and certain other walls thereof being extended, and passing through the apertures in said base and said plate, and being clinched over said plate. 10

3. In combination: an insulating base having an aperture formed therein; plate means, spanning said base aperture, and disposed on one side of said base; receiving means, extending away from the opposite side of said base, and having a recess for receiving an electrical conductor terminal, said receiving means having portions abutting said opposite side of said base, and other portions extending through said base aperture and constructed and arranged with respect to said plate means to hold said plate means and said receiving means to said base; and biasing means, for yieldably engaging and holding a conductor terminal disposed in said receiving means recess, said biasing means having one end bearing on said plate means. 15

4. In combination: an insulating base having an aperture formed therein; plate means, spanning said base aperture and disposed on one side of said base, said plate means having at least one aperture disposed off-center with respect to said base aperture; receiving means, extending away from the opposite side of said base, and having a recess for receiving an electrical conductor terminal, said receiving means having at least one portion abutting said opposite side of said base, and at least one other portion extending through said base aperture and the aperture formed in 40 said plate means, said other portion having a part clinched over said plate means to hold said plate means and said receiving means to said base; and biasing means, for yieldably engaging and holding a conductor terminal disposed in said 45 receiving means recess, said biasing means having one end bearing on said plate means.

5. In combination: an insulating base having an aperture formed therein; plate means, disposed on one side of said base; tubular receiving means, extending away from the opposite side of said base, and having a recess for receiving an electrical conductor terminal, said tubular receiving means having certain wall portions abutting said opposite side of said base, and certain 55 other wall portions extending through said base aperture and constructed and arranged with respect to said plate means to hold said plate means and said receiving means to said base; detent means within said tubular receiving means, for engaging and holding a conductor terminal received in said recess; and spring means within 60 said tubular receiving means, bearing against said plate means, and urging said detent means to operative position. 65

6. Electrical connection means, comprising: a base, having an aperture; a member, disposed on one side of said base and adjacent said aperture; a tubular body, disposed on the opposite side of said base, and having a recess for receiving an 70 electrical conductor, said body having certain wall portions abutting said opposite side of said base, and certain other wall portions extending through said base aperture, and constructed and arranged with respect to said member to hold said 75

member and said body to said base; and biasing means, disposed within said body for yieldably engaging a conductor disposed within said body recess, said biasing means having one end extending through said base aperture and abutting said member.

5. In combination: a base, having an aperture; a sheet-metal tubular body, having a transverse recess for receiving a conductor terminal, and at one end being formed with tongue means, said body being so constructed and arranged that portions struck from said body adjacent said one

end abut one surface of said base, and said tongue means passing through said base aperture to the opposite surface of said base; metal plate means, having one surface abutting said opposite surface of said base, and being apertured to pass said tongue means, said tongue means being bent to overlie the opposite surface of said plate means; and biasing means, having one end bearing against said one surface of said plate means, and the other end in position to yieldably engage a 10 conductor terminal within said body recess.

HARRY A. DOUGLAS.
